UNITED STATES PATENT OFFICE.

CHRISTIAN EDMUNDSON, OF TIENSIN, CHINA.

ELECTRIC-LIGHT ATTACHMENT FOR PENS OR PENCILS.

1,274,022.

Specification of Letters Patent. Patented July 30, 1918.

Application filed May 28, 1917. Serial No. 171,514.

To all whom it may concern:

Be it known that I, CHRISTIAN EDMUNDSON, a citizen of the United States, residing at Tientsin, in the Republic of China, have 5 invented certain new and useful Improvements in Electric-Light Attachments for Pens or Pencils, of which the following is a specification.

My invention relates to electric light attachments for writing pens or pencils and the principal object thereof lies in the provision of a reflector mounted adjacent the pen or pencil point and carrying electric bulbs, the rays of which being thrown upon 15 the writing paper so that a person may see to write in dark and remote places.

A second object of the present invention is to provide an attachment of this character which is detachable from the pen or pencil 20 and which is provided with a switch for closing an electric circuit to supply energy to the lights, that is held in position to close the electric circuit by the forefinger of the writer's hand while writing with the pen 25 or pencil, that it to say the pen or pencil is grasped in the usual way only at a point adjacent the switch.

It is another object of my invention to provide an illuminating attachment for 30 writing implements which is adjustable to any point on the same: for instance in using the attachment upon a lead pencil it will be necessary to shift the same longitudinally at different times owing to the re-sharpening 35 of the pencil.

A further object of the invention is to provide an attachment of the above mentioned character which may be used in conjunction with any conventional pen or pencil.

40 Another object is to provide an illuminating attachment for pens or pencils which consists of a minimum number of parts which are easily assembled and disassembled and which can be manufactured and placed 45 on the market at a minimum cost.

The invention consists of constructions, combinations and arrangement of coöperating elements all of which will be specifically set forth in the following description and 50 illustrated in the accompanying drawing in which,

Figure 1 is an elevation of a pencil having my improved illuminating attachment mounted thereon.

55 Fig. 2 is an elevation taken at right angles

to Fig. 1: part of the pencil being broken away and,

Fig. 3 is a longitudinal sectional view taken on the line 3—3 of Fig. 2.

My improved attachment is especially designed for detectives, policemen and the like but however it may be used by the public in general.

Referring to the drawing wherein like characters of reference designate like parts in all the views the numeral 5 designates a pencil of any conventional type. While I have in this case illustrated a conventional pencil, an ordinary pen or fountain pen may be employed.

70 Mounted on the pencil 5 is a sleeve 6 which is arranged at any point on the same but preferably near the writing point. Extending transversely through the sleeve 6 is a set screw 7 which is adapted for binding 75 engagement with the pen or pencil. This sleeve 6 is formed with a hollow boss 8 in which is mounted a reciprocable push-button 9. Mounted upon the interior of the sleeve 6 and below the hollow boss 8 are resilient 80 contacts 10 and 11.

The numeral 12 designates a reflector which is constructed from any suitable material and is substantially bowl or concavo-convex in cross section. This reflector carries a collar or annulus 13 that is detachably received on the sleeve 6. This reflector is also formed with an inwardly directed flange or shoulder 14 that abuts the lower end of the sleeve 6. What I shall term as the upper 90 edge of the reflector is formed with a forwardly extending extension 15 and is substantially spoon shaped. The function of this extension 15 is to direct the illuminating rays upon the paper rearwardly of and 95 adjacent the point of the pen or pencil.

Mounted in the reflector 12 in any suitable manner and at preferably diametrically opposite points of the pencil are electric bulbs 16. Suitable feed wires are in circuit with 100 the contacts 8 and 10 and the bulbs 16. These conductors are incased in the usual sheathing of non-conducting material designated by the numeral 17.

105 This sheathing 17 extends through an eye 18 mounted on the sleeve 6 and longitudinally of the pencil 5 and then through a second eye 19. The conductors are electrically connected with a battery 21 which is adapted to be carried around in the pockets 110

of the operator or mounted in any other convenient place.

From the above disclosure it will be seen that I have provided a simple, economical, 5 illuminating attachment for pens or pencils which may be used advantageously in dark or poorly lighted places and which is efficient and durable in use.

It will be manifest that in using a pen or 10 pencil having my improved attachment thereon the writer's thumb and fingers are engaged about the sleeve 6 in the manner that an ordinary pen or pencil is manipulated, with the forefinger pressing inwardly 15 upon the push-button 9 which will cause the current to flow from the battery 21 and illuminate the bulbs 16.

This disclosure is merely illustrative and 20 it is to be understood that it is within the realm of my invention to modify and arrange the parts otherwise than herein illustrated and set forth and that I am only limited by the claims herewith appended:

25 What is claimed is:

1. The combination with a pen or pencil, a sleeve longitudinally adjustable thereon, an electrical switch mounted on the sleeve, a reflector formed with a collar accommodated on the sleeve and further provided

with a shoulder which abuts one end of the 30 sleeve, electrical bulbs carried by the reflector and arranged at diametrically opposite points of the pens or pencils, an extension formed with the reflector and overlying the bulbs, and a source of electrical energy in 35 circuit with the bulbs and switch.

2. The combination with a pencil or like marking implement, of a sleeve encircling the same, a reflector surrounding and removably engaged with one end of said 40 sleeve, electric bulbs carried by said reflector, and a switch carried by said sleeve and electrically connected with said bulbs.

3. The combination with a pencil or the like, of an encircling sleeve mounted for 45 longitudinal adjustment thereon a concave reflector provided with a collar embracing said sleeve, an inwardly directed flange carried by the reflector and engaging an end of the sleeve, bulbs carried by said reflector, and a switch carried by said sleeve and electrically connected by said bulbs. 50

In testimony whereof I affix my signature in presence of two witnesses.

CHRISTIAN EDMUNDSON.
